ATTORNEY

UNITED STATES PATENT OFFICE.

SAMANTHA GARLICK, OF MOORESVILLE, MISSOURI.

DESIGN FOR A FLAT-IRON HEATER.

51,493.

Specification for Design.

Patented Nov. 20, 1917.

Application filed September 29, 1917. Serial No. 194,096. Term of patent 14 years.

To all whom it may concern:

Be it known that I, SAMANTHA GARLICK, a citizen of the United States, residing at Mooresville, in the county of Livingston and State of Missouri, have invented a new, original, and ornamental Design for Flat-Iron Heaters, of which the following is a specification, reference being had to the accompanying drawing, forming a part thereof.

Figure 1 is a top plan view of the flat iron heater, showing my new design.

Fig. 2 is a side elevation of the heater, and

Fig. 3 is an end elevation thereof.

I claim:

The ornamental design for a flat iron heater as shown.

SAMANTHA GARLICK.
